UNITED STATES PATENT OFFICE.

GEORGE W. SMITH, OF CHICAGO, ILLINOIS.

TELEPHONE SUPPORT.

Application filed February 14, 1927. Serial No. 168 020

This invention relates to improvements in telephone supports and its prime object is to provide a device of this class that is simple in construction, efficient and durable in use and cheap to manufacture.

With the foregoing and other objects in view the invention consists in the combination and arrangement of parts to be hereinafter fully described, particularly pointed out in 10 the claim and illustrated in the drawing which forms a part of this application and in which—

Fig. 1 is a top plan view of the support attached to a table or flat top desk.

15 Fig. 2 is a view of Fig. 1 in side elevation, the dotted lines denoting the telephone instrument.

Fig. 3 is a rear view of Fig. 2.

20 Fig. 4 is a top plan view of a slightly modified form of the telephone support.

Fig. 5 is a view of Fig. 4 in side elevation.

Fig. 6 is a rear view of Fig. 5.

Like reference characters denote corresponding parts throughout the several views.

25 The telephone instrument as now provided in offices, homes, public places etc. etc. is subjected to considerable abuse. It usually stands unsecured upon small tables, shelves, desks and similar supporting mediums and 30 being frequently moved about in use and often, after use, being placed too near the edge of the support it is liable, and frequently does, fall to the floor with the result that it may be damaged. It is the purpose of the present 35 invention to remedy this condition and to provide means for supporting the telephone securely in position where it may be handy to those having use for it and out of the way when not in use.

40 This telephone support is preferably of one-piece formation thereby enabling it to be manufactured economically. It affords a firm supporting medium for the telephone instrument. Its base or upturned flange may serve 45 as an advertising medium, the advertising matter being printed or stamped thereon or labels carrying the advertisement may be applied thereto.

The telephone support comprises a base 1 50 which may be substantially round in shape, or it may be somewhat oblong with one projecting rounded edge 2, to receive the base of the telephone instrument. If desired this base may be provided upon its under side with 55 a soft pad of felt 3, or like material, to prevent it from marring the surface to which it

may be secured. To facilitate the securing of the base to the table top, desk or other surface 1^a the base is formed with two spaced marginal downwardly extending prongs 4 adapted to receive the screws 5 that fasten it direct to its support and between said prongs with the upstanding flange or stop lug 6 and 90 degrees removed from said lug the base is formed with the opposed marginal inwardly curved tongues or clips 7, the base being formed preferably opposite each tongue 7 with a small round perforation 8 to receive a small screw to further secure it to the supporting surface. This latter means of fastening the base to its support is seldom resorted to unless the nature of the support is such as to make such auxiliary fastening means desirable. The foregoing description has been, in main, directed to the form of device shown in Figs. 1 to 3 inclusive.

In Figs. 4 to 6 inclusive a slightly modified form of the invention is shown. The oblong base 1 is formed along its edge opposite the lip 2 with an upstanding flange 9 disposed at 80 right angles to the base and from the base and flange the downwardly extending tongue 10 is struck, disposed also at right angles to the base, said tongue and flange being formed with the screw receiving perforations 11 85 whereby the device may be secured to a support. Along the lateral edges of the base 1 contiguous to the flange 9 the oppositely disposed downwardly extending parallel wings or prongs 12, 12 are formed and spaced 90 slightly therefrom and contiguous to the lip 2 the upwardly extending inwardly curved marginal tongues 13 are formed. This type of support may be applied to the end of a roll top desk, the flange and tongue 9, 10 being secured to one end of the desk with the wings 12 bracing against this end, or the tips of the wings may rest upon that portion of the table of the desk that projects beyond the sides; or the support may be secured to a partition rail in an office or to any upright support 1^b as shown.

In placing the telephone instrument upon the support the base of the transmitter is disposed upon the base 1 and moved into contact with the flange 9 or stop lug 6. At this time the tongues 7 or 13 will engage with the base of the instrument. The height of the top edge of the flange 9 above the base is such that it will not contact with the telephone receiver when it is in position upon the telephone hook.

What is claimed is:—

In a one-piece support for telephone instruments, an oblong base having one projected rounded edge, an upturned flange formed upon the base opposite said edge and disposed at right angles thereto, downturned parallel prongs formed laterally of said base and contiguous to said flange, a tongue struck from said base and flange jointly and in the common direction of said prongs and dis-

posed between the same and at right angles to said base, and oppositely disposed twin curved tongues extending upwardly from said base contiguous to said rounded edge, all of the before-mentioned elements being permanently fixed with relation to each other, substantially as and for the purpose set forth.

15

In testimony that I claim the foregoing as my own I have hereto affixed my signature.

GEORGE W. SMITH.
